UNITED STATES PATENT OFFICE.

JOSEPH L. BREDAR, OF ROCK ISLAND, ILLINOIS.

DEMOUNTABLE RIM.

1,318,534.

Specification of Letters Patent. Patented Oct. 14, 1919.

Application filed May 14, 1918. Serial No. 234,522.

To all whom it may concern:

Be it known that I, JOSEPH L. BREDAR, a citizen of the United States, residing at Rock Island, in the county of Rock Island 5 and State of Illinois, have invented a new and useful Demountable Rim, of which the following is a specification.

The device forming the subject matter of this application is a demountable rim and 10 one object of the invention is to provide a rim of the type specified, comprising but three parts, the construction being such that the rim may be folded up readily within the area of a half circle of which one of said 15 parts constitutes a portion.

Another object of the invention is to provide novel means for operatively connecting together against movement, the ends of two segments or part of the rim.

20 A further object of the invention is to improve the construction of the joint between the relatively movable ends of two parts of the rim.

It is within the province of the disclosure 25 to improve generally and to enhance the utility of devices of that type to which the present invention appertains. With the above and other objects in view, which will appear as the description proceeds, the invention resides in the combination and arrangement of parts and in the details of construction hereinafter described and claimed, it being understood that, within the scope 30 of what is claimed, changes in the precise embodiment of the invention shown can be made without departing from the spirit of the invention.

In the accompanying drawings:

Figure 1 shows in side elevation, a tire 40 and a rim embodying the present invention; Fig. 2 is a fragmental flange showing a portion of the rim, the inner side thereof being depicted; Fig. 3 is a section taken approximately on the line 3—3 of Fig. 2; Fig. 4 is a 45 section taken approximately on the line 4—4 of Fig. 2; Fig. 5 is a bottom plan showing the securing element which carries the latch.

In carrying out the present invention, there is provided a rim comprising an intermediate segment 1 and terminal segments 2 and 3 hinged at their outer ends as shown at 4 to the ends of the intermediate segment, the inner ends of the terminal segments being disposed in coöperating relation and being disposed approximately opposite to a

point 5 midway between the ends of the intermediate segment 1. The construction is such that the terminal segments 2 and 3 may be folded toward the intermediate segment 1 to lie within the area of a half-circle of 60 which the intermediate segment 1 constitutes a part.

Each of the segments 1, 2 and 3 comprises a base 6 and side flanges 7. The meeting ends of the bases 6 of the terminal segments 65 2 and 3 are disposed radially of the rim, as indicated at 8 in Figs. 3 and 4, whereas, the meeting ends of the side flanges 7 of the segments 2 and 3 are beveled at an angle to the meeting ends 8 of the bases of the segments 70 2 and 3, as shown at 9.

A tongue 10 is secured to the base 6 of the segment 3 and overlaps the base of the segment 2 as clearly shown in Fig. 3, the tongue having an outwardly extended projection 11 75 received in a recess 12 in the base 6 of the segment 2.

A securing element is provided, the same including a stem 14, a body 15 having parallel sides 16, and a head 17 which projects laterally beyond the body 15. The stem 14 of the securing element is mounted in the base 6 of the segment 2. The invention comprises a latch 18 mounted for right-line sliding movement on the segment 2 and adapted to overlap the segment 3. The latch 18 has a longitudinal slot 19 in which the body 15 of the securing element is received and because the body of the securing element is provided with parallel sides 16 which coact with the straight sides of the slot 19, the latch 18 is guided for right-line movement. The head 17 of the securing element overhangs the latch 18 and holds the same on the segment 2 for right-line movement as aforesaid. Adjacent its rear end, the latch 18 is dented or otherwise constructed, as shown at 20, to form a projection 21 coacting with a seat 22 fashioned in the base 6 of the segment 2. The latch 18 is independent 100 of the tongue 10.

In practical operation, the segment 3 is swung outwardly into circumferential alignment with the segment 2, the projection 11 on the tongue 10 being received in the recess 12 of the segment 2. These elements coact to prevent relative circumferential movement between the segments 2 and 3 of the rim. The latch 18 is then slid endwise, until it overlaps the segment 3, and 110

thus, the segment 3 is prevented from swinging inwardly with respect to the part 2, the projection 21 being received in the seat 22 to prevent the rearward movement of the 5 latch 18 and a disengagement of the latch from the part 3.

Attention is directed to the fact that, since the bases 6 of the segments 2 and 3 at their meeting ends are disposed radially of 10 the rim, and since the side flanges 7 are cut off at a bevel, as shown at 9, the structure will remain locked in a circle, even though it is not mounted on a wheel.

The construction of the rim is such that 15 it may be readily assembled with and detached from a tire, which is denoted by the numeral 23 in Fig. 1.

Having thus described the invention, what is claimed is:—

- 20 1. In a device of the class described, a rim comprising a plurality of pivotally connected segments each including a base and side flanges, the meeting ends of two of said segments having relative movement parallel 25 to the median plane of the rim, the meeting ends of the bases of said two segments being disposed radially of the rim, and the meeting ends of the side flanges of said two segments being beveled at an angle to the 30 meeting ends of the bases of said two seg-

ments, and means for releasably connecting the meeting ends of said two segments.

2. A rim comprising parts the ends of which have relative movement parallel to the median plane of the rim; a tongue on 35 one part and extended beyond the end of said part, to overlap the end of the other part, the tongue having a projection, and said other part having a recess in which the projection is received; a latch independent of the tongue and slideable on said other part and adapted to overlap the end of the first specified part, the latch having a longitudinal slot provided with parallel edges; and a securing element including a stem 45 mounted in said other part, a body having parallel sides coacting with the edges of the slot to constrain the latch for right-line sliding movement on said other part and to hold the latch out of the path of the tongue, 50 the securing element including a head overlapping the outer face of the latch on opposite sides of the slot.

In testimony that I claim the foregoing as my own, I have hereto affixed my signature in the presence of two witnesses.

JOSEPH L. BREDAR.
